US0D1053156S

(12) **United States Design Patent** (10) Patent No.: **US D1,053,156 S**
(45) Date of Patent: ** Dec. 3, 2024

(54) **FURNACE FOR SUBSTRATE PROCESSING APPARATUS**

(71) Applicant: **KOKUSAI ELECTRIC CORPORATION**, Tokyo (JP)

(72) Inventors: **Hideto Tateno**, Toyama (JP); **Takatomo Yamaguchi**, Toyama (JP); **Daiki Kimoto**, Toyama (JP)

(73) Assignee: **KOKUSAI ELECTRIC CORPORATION**, Tokyo (JP)

(**) Term: **15 Years**

(21) Appl. No.: **29/849,042**

(22) Filed: **Aug. 8, 2022**

(30) **Foreign Application Priority Data**

Mar. 15, 2022 (JP) ..... 2022-005266 D

(57) **CLAIM**

The ornamental design for a furnace for substrate processing apparatus, as shown and described.

DESCRIPTION

FIG. 1 is a front, top and left side perspective view of a furnace for substrate processing apparatus showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a cross-sectional view taken along line 8-8 in FIG. 6.

The broken lines in FIG. 8 are included for the purpose of illustrating portions of the article that form no part of the claimed design.

1 Claim, 8 Drawing Sheets
